TICKET CABINET

Filed Feb. 16, 1926

FIG. 1

FIG. 2

FIG. 3

FIG. 4

FIG. 5

Inventor
Edward Axberg

Herbert E. Smith

Attorney

UNITED STATES PATENT OFFICE.

EDWARD AXBERG, OF SPOKANE, WASHINGTON.

TICKET CABINET.

Application filed February 16, 1926. Serial No. 88,551.

The present invention relates to improvements in ticket cabinets adapted to contain a plurality of ticket rolls or rolled strips, and from which strips the tickets are successively dispensed by grasping in the hand and pulling. The cabinet is especially adapted for use in railway, theatre and other offices where expedition is required in dispensing numbered tickets and accuracy is necessary in accounting for the sale of the tickets.

In carrying out my invention means are provided for cutting or severing the tickets as they are successively withdrawn from the cabinet, and means are also provided whereby the numbers of the succeeding tickets at the front ends of the strips may readily be ascertained when desired, as for instance when making up the accounts at the end of certain periods, as for a day.

Means are provided for locking the cabinet against removal of the ticket rolls and means are also provided for locking the cabinet against removal of single or successive tickets from a strip or strips, and various other features are utilized in the construction and operation of the device to insure proficiency and accuracy in the performance of its functions.

The invention consists in certain novel combinations and arrangements of parts as will hereinafter be more fully set forth and claimed. In the accompanying drawings I have illustrated one complete example of the physical embodiment of my invention wherein the parts are combined and arranged in accordance with the best mode I have thus far devised for the practical application of the principles of my invention.

Figure 1 is a perspective view of a ticket cabinet embodying my invention, showing by dotted lines the interior parts of the mechanism, and also showing by dotted lines a superimposed unit.

Figure 2 is a transverse vertical sectional view of the cabinet showing a ticket in position to be detached from a roll or strip of tickets.

Figure 3 is an enlarged, sectional, detail view of one of the locking devices for the drop bar or hinged locking bar for the tickets.

Figure 4 is a horizontal, longitudinal sectional view at one end of the cabinet showing a portion of the front plate and one of its locking bolts.

Figure 5 is a detail sectional view of the operating devices for the lock of the front plate of the cabinet.

As shown in the drawings the cabinet is 60 preferably of rectangular shape and suitable dimensions depending upon the size of the ticket rolls, and rests upon a base board 1. The cabinet comprised a bottom plate 2, rear wall 3 and top plate 4, with a front plate 5 65 hinged as at 6 at the top to swing outwardly and upwardly to give access to the interior of the cabinet when required. The end walls 7 and 8 are fashioned with flanges 9 for securely closing the ends of the cabinet and 70 the several parts are secured together in suitable manner.

At regular intervals throughout the length of the cabinet are arranged a number of partitions 10 secured against the rear wall 75 of the cabinet and also the bottom, and terminating adjacent the front plate. The vertically arranged partitions divide the cabinet into compartments in which are contained the rolls 11 of tickets which contact 80 with the back wall and rest upon the bottom of the cabinet. In each compartment is located a guide roller 13 loose upon a longitudinally extending rod 14 which is affixed in the end walls of the cabinet and extends 85 through alined openings in the partitions. The rod is located in proper position so that the ticket roll will contact with the guide roller in the respective compartments to restrain the roll from displacement and guide 90 the strip as a ticket as 12 is pulled from the turning roll. It will be understood that the protruding end of the ticket 12 is grasped in the hand and a pull thereon causes the roll to turn on its axis. When the length of 95 a ticket has been pulled out it is torn off or severed and the remaining tickets are successively detached as will be described.

For locking the front plate 5 I use a pair of long slide bolts 15 and 16 extending from the longitudinal center of the cabinet toward its respective ends and located at the inner side of the plate. These bolts are adapted to slide in guides 17 on the inner face of the plate, and the free ends of the slide 100 bolts engage back of complementary flanges 18 at the front of the end plates and alined with the plate when the latter is in closed locked position. These bolts are pivoted on the ends of a double lever arm 19 which is 105 fixed to oscillate with a shaft 20 that extends through an opening in the front plate locat-

ed at its approximate longitudinal center. A knob 21 is loosely journaled on the shaft at the exterior side of the plate and suitably supported in bearings in the plate, and a key 22 may be inserted between the knob and shaft for coupling these two members together in order that the knob may be turned to retract the slide bolts and release the front plate so that it may be swung open on its upper hinges to gain access to the interior of the cabinet. The key 22 of course is removable and is inserted into the operating parts of the lock only when it is desired to unlock the plate.

15 As seen in Figure 2 the lower edge of the front plate terminates at a point to provide for a longitudinally extending discharge slot of sufficient length to accommodate the passage therethrough of tickets from the several ticket rolls. At the front of the bottom plate is fashioned an inclined delivery plate or guide plate 23 which extends longitudinally of the cabinet below the lower edge of the front plate. In front of the delivery plate is arranged an inclined glass plate 24 and the ticket, as seen in Figure 2 is pulled down over the face of the guide plate 23 and across the under face of the transparent or glass plate 24. The ticket is severed or 20 cut off by means of the lower outer corner or edge of the glass plate, which edge is used as a cutting or tearing edge. The ticket is grasped by the finger placed beneath the glass plate and the strip or ticket is given 25 its initial pull from the cabinet against the lower face of the glass plate. The glass plate is held stationary in end brackets 25 which are grooved to receive it and felt fillers as 26 are interposed between the ends of the plate and the brackets as shown in Figure 3.

40 A drop plate 27 is hinged to the delivery plate at 28 and fashioned with a flange 29. The drop plate is normally open when dispensing tickets, but is turned up against the under faces of the ends of the projecting tickets to hold said ends against the under

50 face of the glass plate when the cabinet is closed. The flange 29 also projects up along the lower outer edge of the glass to prevent access to the ticket ends when the drop plate is closed. For locking the cabinet, as at the end of a day, to prevent access to the ticket ends, the drop plate is turned up on its 55 hinges to the dotted line position in Figure 2 and a key is used in connection with each of the two lock casings 30 at the ends of the drop plate to project the bolts 31 into notches 32 of the end brackets 25.

60 In Figure 1 at 33 a superimposed cabinet is shown in connection with the cabinet described to indicate how the cabinets may be built up in units one upon another where the demand for tickets justifies the use of a number of cabinets.

65 Having thus fully described my invention what I claim as new and desire to secure by Letters Patent is—

70 A ticket cabinet comprising a ticket roll container having a flat bottom, a rear wall, a top wall, closed ends and a front plate hinged to the front top edge of said top wall and having its lower edge disposed in slightly spaced relation above said bottom to form a ticket slot, means for locking said 75 front plate in closed position, an inclined glass cover plate disposed over the ticket slot and having its forward edge placed to form a ticket cutter, an inclined delivery flange formed on the front edge of said container bottom beneath said cover plate and parallel thereto, said flange terminating inwardly of the outer edge of said cover plate to provide a finger clearance, a drop plate 80 hingedly suspended from the forward edge of said delivery flange to hang in finger clearing position, said drop plate being formed for closing the ticket slot by being swung upwardly in abutting relation to said cover plate, and means for locking said drop plate in slot closing position.

85 90 95 In testimony whereof I affix my signature.

EDWARD AXBERG.
